Primary Examiner — Natasha Vujcic*Assistant Examiner* — Gilbert B Ford(74) *Attorney, Agent, or Firm* — Revolution IP, PLLC(57) **CLAIM**

The ornamental design for a cylinder for drug injector, as shown and described.

DESCRIPTION

FIG. 1 is a perspective view of a cylinder for drug injector showing a new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in FIG. 4 depict portions of the cylinder for drug injector that form no part of the claimed design.

1 Claim, 4 Drawing Sheets(56)
